UNITED STATES PATENT OFFICE.

ALBERT BONIME, OF CHICAGO, ILLINOIS, ASSIGNOR TO M. MANDEL AND L. MANDEL, OF CHICAGO, ILLINOIS.

BAG-LOCK.

1,157,364.

Specification of Letters Patent.

Patented Oct. 19, 1915.

Application filed September 21, 1914. Serial No. 862,659.

To all whom it may concern:

Be it known that I, ALBERT BONIME, a subject of the Czar of Russia, and resident of Chicago, county of Cook, and State of Illinois, have invented certain new and useful Improvements in Bag-Locks, of which the following is a specification.

This invention relates to improvements in bag locks, particularly adapted, though not necessarily limited in its use with pocket-books or purses, and one of the objects of the same is to improve and simplify locks of this character and to produce a lock which will be effective and positive in operation.

15 A further object is to provide an improved lock of this character having a safety attachment in connection therewith, adapted to be rendered active or inactive at the will of the operator.

20 To the attainment of these ends and the accomplishment of other new and useful objects as will appear, the invention consists in the features of novelty in substantially the construction, combination and arrangement 25 of the several parts, hereinafter more fully described and claimed and shown in the accompanying drawing illustrating the invention, and in which—

Figure 1 is a top plan view of a portion of 30 a bag having a lock applied thereto constructed in accordance with the principles of this invention. Fig. 2 is a detail vertical sectional view taken on line 2—2, Fig. 1. Fig. 3 is a view similar to Fig. 2 showing in 35 full lines the parts of the lock in a different position. Fig. 4 is a view similar to Fig. 1 of a modified form of the invention. Fig. 5 is a detail sectional view taken on line 5—5, Fig. 4. Fig. 6 is a detail top plan 40 view of one of the elements of the lock shown in Fig. 1. Fig. 7 is a detail top plan view of one of the elements of the lock shown in Figs. 4 and 5. Fig. 8 is a detail view partly in section showing another form 45 of lock. Fig. 9 is a vertical sectional view of still another form of lock.

Referring more particularly to the drawing, the numerals 10 and 11 designate the two members of the bag frame which are 50 to be connected, a handle 12 being shown as connected with one of the members.

The lock proper comprises an element 13, which is preferably shaped of a substantially thin flat body, having a slot there- 5 through, and which slot is preferably pro-

vided with an enlarged portion as at 14, while the remaining portion 15 of the slot is reduced. This element 13 is pivotally connected with one of the members of the frame, in any desired or suitable manner, here shown as being connected by means of ears or projections 16 pivotally mounted in posts or bearings 17, and which latter are formed and secured in any suitable manner to one of the frame members. The element 13 is preferably of a length to extend across and beyond the other member of the frame when the members are in a closed position, to form a projection by means of which the member 13 may be moved about its 70 pivot.

A button designated generally by the reference numeral 18, in the form of the invention shown in Figs. 1 to 3, is rotatably secured in any suitable manner to the other member of the frame and this button 18 is provided with an enlarged portion 19, of a size and configuration to fit within the opening 14 of the slot in the element 13, when the latter is in the position shown in Figs. 1 and 2, and to substantially fill the opening 14, and the enlarged portion 19 is also of a size that the top thereof will be substantially flush with the top of the element 13 when the latter is in a locking position. The upper portion of the button 18 is also enlarged as at 20 to form laterally projecting portions 21 that are adapted to extend transversely of the slot in the button 13, when the element 18 is rotated, and thereby lock the element 13 against movement and the frame of the bag closed. The laterally projecting portions 21 of the button 18 are provided as a safety device. When the portions 21 are in a position to extend lengthwise of the slot 15 in the element 13, the shoulders formed by the enlarged opening 14 coöperating with the enlarged portion 19, will serve as a lock to prevent the separation of the members 10 and 11 of the frame, but when the button 18 is turned into the position shown in Fig. 1, the laterally projecting portions 21 serve as an additional and safety locking device.

In the form of the invention shown in Fig. 4 the element 13 is provided with a slot 22 having an enlarged portion 22^a, but which enlarged portion instead of being circular is angular, here shown as being rectangular. In this form of the invention, the button 23 corresponding with the button 18 110

is shaped to form a head 24 having laterally projecting portions corresponding with the portions 21 of the button 18, and is also shaped to form a stem 25 which passes through an element 26 and which element is of a configuration in cross section to conform to the contour and shape of the enlarged portion 22^a of the slot 22, and is held against rotation in any suitable manner, so that the button 24 may be rotated with respect thereto to cause the laterally projecting portion to extend across the member 13.

A spring 27 may be provided to coöperate with the element 13, preferably arranged between the posts 17 and beneath the element, and a portion of the element adjacent the spring is so shaped to coöperate with the spring that the spring will hold the element in the position shown in full lines or in the position shown in dotted lines shown in Fig. 3.

In the form of the invention shown in Fig. 8, the element 29 which corresponds to the element 13 is provided with a slot 30 and is so constructed that the sides 31 of the slot will be resilient. A portion of the slot preferably intermediate its ends is enlarged as at 32, the diameter of the enlargement 36 which extends lengthwise of the slot being slightly greater than the diameter of the portion which extends transversely of the slot, and the sides 31 of the element 29 are provided with recesses 33 to form shoulders 34. The button 35 in this form of the invention which corresponds with the button 18 in the forms shown in Figs. 1, 2 and 3, is provided with an enlargement which is of an oval shape in cross section, and which 40 enlargement corresponds with the enlargement 29. In this form of the invention when the button passes through the slot 30, the enlargement 35 will be in the position shown, and will substantially fill the opening 32. In order to lock the parts, the button 32 is rotated and during this rotation the extremities of the oval portion of the enlargement will engage the shoulders 34 according to the direction of rotation of the 50 button and will spring the sides 31 of the element away from each other or into the position shown in dotted lines. At the same time the ends of the oval portion will spring into the recesses 33 and will be retained in this position until the button is again rotated, when the elastic sides 31 will assume their normal position. With this form of the invention it will be manifest that the user can readily ascertain when the parts of 60 the lock are in such a position that the lock can be opened and also when they are in such a position that they cannot be opened, rendering it unnecessary to look at the lock when it is being operated. This construction also insures the proper positioning of

the parts with relation to each other to enable the separation of the parts.

In the form of the invention shown in Fig. 9, the element 35 corresponding with the element 13 is provided with a slot 36 through which the portion 37 of the button passes and the body 38 of the button will also enter a portion of the slot, the portion 37 of the button being adapted to be turned transversely of the slot. This element 35 is preferably of a slightly springy nature, being shaped to form a nose or projection 39, the extremity of the element having a finger hold 40. The element 11 of the bag frame is provided with a nose or projection 41 with which the projection 39 on the element 35 coöperates, so that when the element 35 is passed over the coöoperating button 37, the projections 39, 41 may be sprung into engagement with each other and serve as a safety catch for holding the parts against accidental separation.

With this improved construction it will be manifest that all of the parts may be formed of stampings and the parts may be secured in position in any desired or suitable manner.

While the preferred forms of the invention have been herein shown and described, it is to be understood that various changes may be made in the details of construction and in the combination and arrangement of the several parts without departing from the spirit of this invention.

What is claimed as new is:—

1. A bag lock embodying a slotted element pivotally connected with a frame member, a button connected with another frame member and adapted to enter the slot and project beyond the first said element, a portion of the said button adapted to be moved to extend across the slot and over the face of the slotted member, and means for maintaining the said button in locking and in unlocking positions.

2. A bag lock embodying a slotted element pivotally connected with a frame member, a button connected with another frame member and adapted to enter the slot and project beyond the first said element, a portion of the said button adapted to be moved to extend across the slot and over the face of the slotted member, and yielding means for maintaining the said button in its adjusted positions.

3. A bag lock embodying a slotted element pivotally connected with a frame member, a button connected with another frame member and adapted to enter the slot and project beyond the first said element, a portion of the said button adapted to be moved to extend across the slot and over the face of the slotted member, a portion of the said button within the slot, being of a greater diameter in one direction than in the

other, the sides of said slot adapted to yield when the said portion of the button is moved crosswise of the slot, the said sides of the slot also having recesses to receive portions 5 of the said button.

4. A bag lock embodying a slotted element pivotally connected with a frame member, a portion of said slot being enlarged and a button connected with another 10 frame member, said button embodying a portion shaped to conform to and substantially fill the said enlarged portion of the slot, said button also embodying a portion shaped to pass through the remaining portion 15 of the slot and beyond the other element and to be moved transversely across the slot and over the face of the slotted element when the two elements are connected, one extremity of the first recited element extending beyond the edge of the outer face of 20 the second recited frame member to form a finger engaging portion.

5. A bag lock embodying separable elements, one of said elements connected with 25 one of the frame members of the purse and pivoted to extend transversely of both frame members when the latter are in a closed position with respect to each other and provided with a slot therethrough, said slot

having an enlarged portion, the other of said elements comprising a button connected with the other frame member and adapted to pass through the said slot, the said button having an enlarged portion entering and substantially filling the said enlarged portion 35 of the said slot.

6. A bag lock embodying a slotted element pivotally connected with a frame member, said slot having a portion the diameter of which is greater in one direction than in another direction, a button connected with another frame member and adapted to be inserted into and removed from said portion of the slot and conforming 40 to the shape thereof, and provisions 45 whereby the said button may be moved in the slot so that the greater diameter thereof will extend in the direction of the smaller diameter of the said slot.

In testimony whereof I have signed my name to this specification, in the presence of two subscribing witnesses, on this 18th day of September A. D. 1914.

ALBERT BONIME.
